UNITED STATES PATENT OFFICE.

JOSEPHI SLAWIK, OF BLOOMFIELD, NEW JERSEY.

ORGAN-ACTION.

SPECIFICATION forming part of Letters Patent No. 623,843, dated April 25, 1899.

Application filed March 8, 1898. Serial No. 673,064. (No model.)

To all whom it may concern:

Be it known that I, JOSEPH SLAWIK, of Bloomfield, in the county of Essex and State of New Jersey, have invented a new and Improved Organ-Action, of which the following is a full, clear, and exact description.

The invention relates to organs having an upper and lower keyboard; and the object of the invention is to provide a new and improved organ-action whereby either keyboard when played causes a sounding of its corresponding sounding devices, and by the use of the desired couplings the playing of one of the keyboards causes a sounding of both sets of sounding devices simultaneously to produce a grand-organ effect in a very simple manner.

The invention consists of novel features and parts and combinations of the same, as will be described hereinafter and pointed out in the claims.

Reference is to be had to the accompanying drawings, forming a part of this specification, in which similar characters of reference indicate corresponding parts in all the figures.

Figure 1 is a sectional side elevation of the improvement. Fig. 2 is a sectional side elevation of the action for one of the sounding devices with the parts in a different position from that shown in Fig. 1. Fig. 3 is an enlarged sectional side elevation of the intermediate coupler-action, the section being taken on the line 3 3 of Fig. 4. Fig. 4 is a transverse section of the same on the line 4 4 of Fig. 3. Fig. 5 is a reduced front elevation of the keyboard, and Fig. 6 is an enlarged transverse section showing the coupler-tube connections.

As illustrated in Fig. 1, the great-action A and the swell-action A' are provided for controlling the air to the sounding devices B B' on the said actions. The latter are controlled from valves C C', respectively connected by stickers D D', respectively, with the lower and upper keyboards D² and D³, respectively, (see Fig. 5,) so that when playing either keyboard, the corresponding sounding devices B or B' are sounded.

Intermediate of the valve C' and its action A' is arranged a coupler-action E, adapted to be actuated from valves similar to valve C and controlled by the coupler draw-stops D⁴, D⁵, and D⁶ to permit of actuating both ac-

tions A A' simultaneously upon playing the keys of the lower keyboard, as hereinafter more fully described.

The actions A A' are alike in construction and similar to the one shown and described in the application for Letters Patent of the United States, Serial No. 630,389, filed April 2, 1897, and allowed August 25, 1897. As the actions A and A' are alike in construction it suffices to describe but one. Each action has a wind-chest F, into which open the metallic tubular seats B², leading to the sounding devices B and B', in the form of reeds, pipes, or the like, and each seat B² is normally closed by a diaphragm-valve G for preventing the wind from the wind-chest from passing to the corresponding sounding device B or B' unless the corresponding key is pressed by the operator, as hereinafter more fully described.

Each diaphragm-valve G is adapted to close an opening H', leading to an exhaust-passage H, having two valve-seats H² H³, of which the latter opens to the atmosphere, and the valve-seat H² connects with a wind-chest I, as plainly shown in Figs. 1 and 2. Valves J J', secured on a valve-stem J², are adapted

to be alternately seated on the seats H² H³—that is, when the valve J' is on its seat H³ then the valve J is off its seat H²—so that air from the wind-chest I can pass into the passage H and through the opening H' to press against the under side of the diaphragm-valves G and hold them to their seats B², so as to prevent the air from the wind-chest F passing to the sounding device. (See Fig. 1.)

When the valve-stem J² moves upward, the valve J engages the seat H² to cut off the connection between the wind-chest I and the corresponding passage H, and at the same time the valve J' moves into an open position to allow the wind in the passage H to escape through the valve-seat H³ to the atmosphere. When this takes place, the preponderance of pressure on the top of the diaphragm-valve G causes the latter to move downward over the opening H' to open the valve-seat B², so that the air from the wind-chest F can pass to the sounding devices and sound the same. (See Fig. 2.) Now in order to move the valve-stem J² and its valves in the direction described I provide the following device:

On the valve-stem is fastened a diaphragm

J^3 , separating the wind-chest I from the duct K, connected by a tube L with a chamber C^2 , forming part of the valve C and normally opening by a pallet C^3 into the wind-chest C^4 .
 5 The pallet C^3 is also connected with a pallet C^5 , connected with the sticker D and serving to connect the chamber C^2 with the atmosphere to exhaust air from the chamber C^2 at the time the pallet C^3 is closed—that is, when
 10 the corresponding key of the lower keyboard D² is pressed. Now when the key is pressed and air is permitted to escape from the chamber C^2 then a reduction of pressure takes place in the duct K, so that pressure from
 15 the wind-chest I against the diaphragm J^3 moves the latter upward and lifts the valves J J', so as to close the seat II² and to open the exhaust-seat II³, as previously explained and for the purpose mentioned. A similar action
 20 takes place in the sounding-device action A' when the keys of the upper keyboard D³ are pressed. The duct K' of this action A' is connected for the purpose mentioned by pipes L' with passages E' in the coupler-action E, and
 25 said passages are connected by pipes E² with the chamber C^6 in the valve C', which valve has the pallets C⁷ C⁸, of which the former connects the wind-chest C^9 with the chamber C^6 , and the other pallet C⁸ connects the chamber
 30 C⁶ with the outer air. Normally the pallet C⁸ is closed and the pallet C⁷ is open, and both are actuated simultaneously from the upper keyboard D³ on pressing the corresponding key—that is, when a key on the
 35 upper keyboard is pressed the pallet C⁸ is opened and the pallet C⁷ is closed—so that an exhaust of air takes place in the chamber C⁶, the pipe E², the passage E', the pipe L', and the duct K' to actuate the valve J for
 40 the action A', the same as previously explained in reference to the action A, and consequently the corresponding sounding devices B' are sounded.

Between the keyboards D² and D³ are arranged the coupler draw-stops D⁴ and D⁵, and a similar coupler draw-stop D⁶ is located below the keyboard D². Each coupler draw-stop is normally in an outermost position; but each is adapted to be pushed inward by
 45 the organist to open a valve similar to the valves C or C', connected with the coupler-action E, as hereinafter more fully described, to bring in all or some of the sounding devices of the action A'. The coupler D⁴ when
 50 pressed inward brings the entire action A' and its sounding devices B' in play when the keyboard D² is played—that is, the sounding devices B are reinforced by the corresponding sounding devices B'. When the coupler
 55 D⁵ is pressed in its valve exhausts air from the coupler-action E and that of action A' in such a manner that only sounding devices B' an octave higher than the devices B sounded at the same time are brought into action, and
 60 when the coupler D⁶ is pressed sounding devices B' an octave lower than those sounded at B are called simultaneously into action.

Thus by manipulating the couplers as described the player is enabled to bring the whole or part of the sounding devices B' into action when playing on the lower keyboard only to reinforce the sounds emitted by the sounding devices B with the corresponding ones from the sounding devices B', either of the same quality or an octave higher or lower. 70
 75 When it is desired to move a coupler out of action, a button D⁷ alongside each coupler draw-stop is pushed inward to close the valve and return the coupler draw-stop to an outermost position. Now in order to make pneumatic connections with the sounding devices B', as above described, I provide the following arrangement on the coupler-action:

In the passage E' is arranged a valve N, secured on a vertically-disposed valve-stem N' 85 and controlling an outlet E³ for connecting the passage E' with the atmosphere. Normally the valve N closes the outlet E³, but is adapted to move upward against a valve-seat E⁴ for closing the passage E' to the pipe E² 90 and for opening the passage E' to the outer air for a reduction of pressure in the pipe L' and the duct K' for sounding the sounding device B' when a corresponding key of the lower keyboard is played, so that both sounding devices B B' are simultaneously sounded for grand-action effect and as before mentioned. The shifting of the valve N into this position is controlled by either or all of the coupler draw-stops D⁴, D⁵, and D⁶, and for this purpose I provide the following arrangement, special reference being had to Figs. 1, 3, and 4: Each valve-stem N' above the valve N extends in a passage E⁵ and passes through a number of diaphragms N² N³ N⁴ in 105 the said passage E⁵ for controlling the movement of the valve N, each diaphragm being engaged at its top by a collar N⁵, secured on the valve-stem N'. Thus a preponderance of pressure against the under side of one of the diaphragms will move the same upward and in doing so carry along the collar N⁵ and stem N' to shut the valve N without disturbing the position of the other diaphragms as the stem slides loosely through the same. 110

The uppermost diaphragm N⁴ has its top chamber P normally closed by a diaphragm P', which when open or in an uppermost position connects the said chamber with a pipe L², leading to the corresponding pipe L, connecting the action A with the valve C. The chamber P² over the diaphragm P' is connected by a pipe P³ with the air-chamber of the valve for the coupler draw-stop D⁴, so that when the latter is pushed in the pallet in the coupler-valve is opened and air escapes to reduce the pressure in the pipe P³ and chamber P². The preponderance of pressure from the pipe L² moves the diaphragm P' upward, and when a key on the lower keyboard D² is now 120 played the air from the corresponding pipes L and L² is exhausted to reduce the pressure on top of the diaphragm N⁴, and as there is pressure against the under side of the said 130

diaphragm the latter will move upward, carrying along the stem N' and valve N , to open the passage E' to the atmosphere for actuating the action A' and sounding the corresponding sounding device B' in addition to the corresponding one of the sounding devices B . When the coupler draw-stop D^4 is closed, air from its valve passes into the chamber P^2 to press the diaphragm down, and thereby cut off the pipe L^2 from the chamber P . The diaphragm N^4 by the weight of the valve N and the pressure on the top thereof will move downward to allow the stem N' and valve N to move in the same direction for the valve to close the exhaust E^3 and to again connect the passage E' with the pipe E^2 to allow air to pass to the action A' and close the valves J' and G to stop the passage of the air to the sounding devices B' , as before explained.

From each passage E^5 , under the corresponding diaphragm N^4 and over the diaphragm N^3 , leads a channel O to a chamber O' , connected by a pipe O^2 with a pipe L^2 of an octave lower than that controlled by the valve N . A diaphragm O^3 normally closes the chamber O' to disconnect the channel O and pipe O^2 , and the chamber O^4 on top of the said diaphragm is connected by a pipe O^5 with the valve for the coupler draw-stop D^5 . The action is the same as described above in regard to the diaphragm P' and its connections, except that when the coupler draw-stop D^5 is pushed in and air is exhausted from the chamber O^4 to allow the pressure from the pipe O^2 to act on the diaphragm, and when one of the keys of the keyboard D^2 is now played air is exhausted from the passage E^3 above the diaphragm N^3 , so that the latter is actuated by pressure from below, and the valve N opens the exhaust to bring the action A' into use to sound the same tone, only an octave higher than that sounded by the corresponding sounding device B . A similar arrangement is made relative to the diaphragms N^2 and N^3 , as a channel Q leads from the passage E^5 between the said diaphragms to a chamber Q' , connected by the pipe Q^2 with a pipe L^2 an octave lower than that controlled by the valve N . The chamber Q' is normally cut off from the pipe Q^2 by the diaphragm Q^3 , having its top chamber Q^4 connected by a pipe Q^5 with the valve for the coupler draw-stop D^6 . When the latter is pushed in, air is exhausted from the chamber Q^4 to allow the air from the pipe Q^2 to open the diaphragm Q^3 and connect the pipe with the passage E^5 over the diaphragm N^2 . Now when a key on the keyboard D^2 is played air is exhausted from the passage E^5 over the diaphragm N^2 , so that the latter is forced upward by pressure from below and the valve N opens the exhaust E^3 to actuate the sounding device B' an octave lower than that of the device B sounded by playing the key on the keyboard D^2 , as before explained.

From the foregoing it will be readily understood that any one or all of the coupler draw-stops D^4 , D^5 , and D^6 may be in an innermost

position for the player to call in additional sounds from the sounding devices B' when playing on the keyboard D^2 and sounding the sounding devices B . Thus by the intermediate pneumatic coupler-action E the player is enabled to make use of both sounding-device actions A A' when playing the lower keyboard D^2 , and the said actions A A' can be used independently by the operator playing on the corresponding keys of the lower and upper keyboards at the time the couplers are not in action and the valve N is in the position shown in the drawings. 80

Having thus fully described my invention, I claim as new and desire to secure by Letters Patent—

1. In an organ-action, an exhaust-valve over an outlet in the passage leading from the valve of the upper keyboard to its action, a pneumatically-actuated device for raising said valve, a passage leading from said device to the valve of the lower keyboard, a diaphragm normally closing said passage, and a draw-stop provided with a valve to exhaust air from said diaphragm to raise the same to open said passage, as set forth. 85

2. In an organ-action, an exhaust-valve over an outlet in the passage leading from the valve of the upper keyboard to its action, a passage leading from the valve of the lower keyboard, a diaphragm normally closing said passage, a draw-stop provided with a valve to exhaust air above said diaphragm and raise the same to open said passage, and means for raising said exhaust-valve upon the opening of the valve for the lower keyboard when the passage is open, said means being located between the diaphragm and the exhaust-valve 100 and connected with the latter, as set forth. 105

3. In an organ-action, a pneumatic coupler-action consisting of an exhaust-valve over an outlet in the passage leading from the valve of the upper keyboard to its action, a diaphragm on the stem of said valve, a passage above said diaphragm, said passage communicating with the valve for the lower keyboard whereby to raise said diaphragm and exhaust-valve when the other valve is opened, a diaphragm normally closing said passage, and provided with an air-chamber thereabove and a draw-stop having a valve communicating with said air-chamber to exhaust air therefrom whereby to raise said last-named diaphragm, as set forth. 110 115 120

4. In an organ-action, pipes connecting the valve for the lower keyboard with its action, a coupler-action having pipes connected to said first-named pipes, an exhaust-valve covering an outlet in the passage leading from the valve of the upper keyboard to its action, pneumatically-actuated devices for raising said exhaust-valve when the valve for the lower keyboard is opened and means for establishing and cutting off communication between the pipes leading from said lower keyboard to its action and such devices, as set forth. 125 130

5. An organ-action, provided with a pneumatic coupler-action comprising an exhaust-valve over an outlet in the passage between the upper keyboard-valve and its action, a series of diaphragms on the said valve-stem of the said valve, air-chambers over the said diaphragms, and coupler draw-stops for exhausting the air from the said chambers, and connections with the said diaphragms from the valves of the lower keyboard to actuate the said exhaust-valve on playing the keys of the said lower keyboard, substantially as shown and described.
6. An organ-action, comprising a plurality of sounding-device actions, valves independently controlled from the keys of the upper and lower keyboards, the valves controlling the said actions, an intermediate coupler-action in the connection between the upper keyboard-valve and its action, said coupler-action being controlled by the valves for the lower keyboard, said coupler-action comprising an exhaust-valve over an outlet in the passage between the upper keyboard and its action, a diaphragm on the valve-stem of said valve, an air-chamber over the said diaphragm and connected with the valve for the lower keyboard, and a wind-chest under the control of the coupler draw-stop, and connected with a diaphragm for connecting or disconnecting the said chamber with or from the valve of said lower keyboard, substantially as shown and described.
7. An organ-action, provided with a coupler-action having passages for connecting the valves of the upper keyboard with the sounding-device actions, an exhaust-valve over an outlet leading from each passage to the atmos-

phere, a series of diaphragms on the stem of the said exhaust-valve, an air-chamber connected with the valves for the lower keyboard, a diaphragm for connecting and disconnecting the air-chamber with and from the valve-stem diaphragms, and a wind-chest controlled by the coupler draw-stop and opening onto the said air-chamber diaphragm, to close the latter and the valve-stem diaphragms, substantially as shown and described.

8. In an organ-action, a pneumatic coupler-action consisting of an exhaust-valve over an outlet in the passage between the valve of the upper keyboard and its action, a series of diaphragms on the stem of said exhaust-valve, passages above each diaphragm and leading to the valve for the lower keyboard, and a coupler draw-stop arranged to open and close each of said last-named passages, as and for the purpose set forth.

9. In an organ-action, a pneumatic coupler consisting of an exhaust-valve over an outlet in the passage leading from the valve of the upper keyboard to its action, a series of diaphragms on the stem of said exhaust-valve and each independent of the others in its movement, passages above each diaphragm and leading to the valve of the lower keyboard, diaphragms closing and opening said latter passages, and a coupler draw-stop connected with each of said latter diaphragms to pneumatically raise and lower the same, as and for the purpose set forth.
